CLAIM

The ornamental design for a sample handling device, as shown and described.

DESCRIPTION

FIG. 1 is a front, top, and right side isometric view of a sample handling device showing our new design

FIG. 2 is a rear, bottom, and left side view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The dash-dot broken lines illustrate portions of the sample handling device that form no part of the claimed design.
